UNITED STATES PATENT OFFICE.

CONOVER T. SILVER, OF NEW YORK, N. Y.

DESIGN FOR AN AUTOMOBILE-TOP.

50,252.

Specification for Design.

Patented Jan. 30, 1917.

Application filed October 28, 1916. Serial No. 128,330. Term of patent 14 years.

To all whom it may concern:

Be it known that I, CONOVER T. SILVER, a citizen of the United States, residing in the city of New York, county of New York, and State of New York, have invented a new, original, and ornamental Design for Automobile-Tops, of which the following is a specification, reference being had to the accompanying drawing, forming part thereof.

Figure 1 is a side elevation of the automobile top, showing the vehicle in dotted lines.

Fig. 2 is a rear elevation.

I claim:

The ornamental design for an automobile top, as shown.

Dated, New York, October 10th, 1916.
CONOVER T. SILVER.

Witnesses:

H. J. SHORTER,
L. W. EASTON.
